DISPOSABLE SYRINGE

Harry Gilbert Willis, Blackwood, South
Australia, AustraliaApplication July 2, 1951, Serial No. 15,747
In Australia March 9, 1951

Term of patent 14 years

(Cl. D83—1)

To all whom it may concern:

Be it known that I, Harry Gilbert Willis, a subject of the King of Great Britain, residing at Wilpenna Street, Blackwood, State of South Australia, Commonwealth of Australia, have invented a new, original, and ornamental Design for a Disposable Syringe, of which the following is a specification, reference being had to the accompanying drawing, forming a part hereof.

Fig. 1 is a side elevation of a disposable syringe embodying my new design in closed position for storage or transport;

Fig. 2 shows the combined needle cover and push rod, and also the sealing plug, removed;

Fig. 3 shows the syringe as in use when giving an injection;

Fig. 4 is a front end elevation of Fig. 1,

Fig. 5 is a rear end elevation of Fig. 1,

Fig. 6 is a rear end elevation of the combined needle cover and push rod, and

Fig. 7 is a rear end elevation of the main barrel.

I claim:

The ornamental design for a disposable syringe, as shown.

HARRY GILBERT WILLIS.
